SERVING TRAY FOR AUTOMOBILES

John E. Ferguson, Excelsior Springs, Mo., assignor
to Avsco, Incorporated, Kansas City, Mo., a cor-
poration of Missouri

Application July 16, 1952, Serial No. 20,646

Term of patent 3½ years

(Cl. D44—10)

To all whom it may concern:

Be it known that I, John E. Ferguson, a citizen of the United States, residing at Excelsior Springs, in the county of Clay and State of Missouri, have invented a new, original, and ornamental Design for a Serving Tray for Automobiles, of which the following is a specification, reference being had to the accompanying drawing, forming a part thereof.

Fig. 1 is a perspective view of a serving tray for automobiles, showing my new design;

Fig. 2 is an end elevational view thereof; and
Fig. 3 is a bottom plan view thereof.

I claim:

The ornamental design for a serving tray for automobiles, as shown.

JOHN E. FERGUSON.
